UNITED STATES PATENT OFFICE.

WILLIAM D. KYLE, OF MILWAUKEE, WISCONSIN.

LINE-CONDUCTOR SUPPORT.

1,282,876.

Specification of Letters Patent. Patented Oct. 29, 1918.

Application filed October 23, 1916. Serial No. 127,104.

To all whom it may concern:

Be it known that I, WILLIAM D. KYLE, a citizen of the United States, and resident of Milwaukee, in the county of Milwaukee, 5 and State of Wisconsin, have invented new and useful Improvements in Line-Conductor Supports, of which the following is a description, reference being had to the accompanying drawings, which are a part of this specification.

The invention relates to line conductor supports.

The invention is more particularly designed to provide a line insulator and support for the same.

Formerly it has been the practice to fixedly secure the insulator to an attaching bracket, but it frequently happens that when a line conductor is strung from a pole to the 20 wall of a house that an attaching means cannot be put up squarely in line with the wall of the house owing to the direction in which the line is coming from the pole and it is necessary to incline the attaching bracket 25 and the insulator with respect to the wall of the house, a thing which is not always easy to do. To obviate this difficulty I have provided a combined insulator and supporting bracket which is known as a hook and knob.

30 When the attaching bracket is put up on the side of a house the insulator may adjust itself to the direction from which the line is coming from the pole, this being made possible through a universal joint connection between the insulator and the bracket, thus permitting the bracket to be put up on the side of a house or wall without any special reference to the position of the insulator.

40 The invention is further designed to provide an insulator with a bail or equivalent part which can be readily attached to its supporting bracket either before or after the bracket is put up.

45 The invention further consists of the several features hereinafter set forth and more particularly defined by claim at the conclusion hereof.

In the drawings:

50 Figure 1 is a plan view of the device, parts being broken away;

Fig. 2 is a side view of the device;

Fig. 3 is a section taken on the line 3—3 of Fig. 1;

55 Fig. 4 is a sectional view of a modified form of attaching bracket;

Fig. 5 is a sectional view of another modified form of attaching bracket;

The device consists of an insulator 6, attaching bracket 7, and a universal joint connection between said insulator and said bracket.

The insulator may be of any kind, the one in the drawing being shown as a simple form of spool insulator 6 having a peripheral groove 8 therein and a central transverse hole or aperture 9.

In Figs. 1 to 3 inclusive the bracket 7 consists of a steel screw 10 for attaching the bracket to a fixed support and about which the body of the bracket is cast. The body of the bracket consists of a broad, flat base 11, an intermediate square-shaped portion 12 and a bendable hook 13. To efficiently secure the screw 10 in the body of the bracket, 75 said screw is provided with a peripheral groove 14 into which a portion of the metal forming the bracket flows when the same is cast onto the screw. The intermediate portion 12 of the bracket is made square-shaped, as shown in Fig. 3, to permit of the use of a wrench to screw the bracket into place on the fixed support.

In Fig. 4 the bracket consists of a steel screw 15 having a bendable hooked end 16 85 and a cast metal portion 18 is cast about the screw 16 to form a broad, flat base 19 and a square-shaped portion 20 similar to portion 12 previously described. The screw 15 is also provided with a peripheral groove 21 90 into which a portion of the metal forming the cast part 18 flows to secure a firm union between the steel screw 15 and the cast metal portion.

In Fig. 5 the bracket 7 consists of an 95 eye-bolt 22 having a pointed screw-shaped end 23 for screwing it into a fixed support and a cast metal portion 24 cast about the eye-bolt and provided with a broad, flat base 25 and a square-shaped portion 26 similar to the portion 12 previously described. The groove 27 is similar to the groove 14 and is provided in the eye-bolt for a similar purpose of securing a close union between the steel and the cast metal part.

The universal joint connection between the bracket 7 and the insulator 6 consists of a wire bail 28 which is hooked on to either the hooks 13 and 16 or is passed through the eye 29 of the eye-bolt 22, and the ends 30 110 of said bail are bent upon themselves for receiving a bolt 31 which passes through the

hole 9 in the insulator 6, the ends of the bail being secured between the head of the bolt and the nut 32. Through the agency of the bail 28 loosely connected to the bracket 7 the insulator 6 may be adjusted at any desired angle with respect to the attaching bracket 7.

With the construction of bracket above described it will be noted that the broad, flat base takes the strain off the screw on the side pull and the hook or eye is in line with the screw on the straight pull so that the tensional pull is resisted by the tension strength of the bracket, all the metal of which is in tension.

It will also be noted in connection with the eye-bolt construction that the eye-bolt cannot be turned no matter in what position the insulator may be adjusted.

The invention thus exemplifies a simple and efficient means for combining an in-

sulator with a readily attachable and simply constructed bracket whereby the insulator may be self-adjusted with respect to said bracket to facilitate putting up the line conductor.

What I claim as my invention is:—

In a line conductor support, the combination of a bracket having a base, a hooked end and a screw integral with the bracket and extending outwardly from the base, an insulator having a groove therein forming a line guide, a bail having eyed ends, a bolt passing through said eyed ends and the insulator to secure the insulator to the bail, the intermediate portion of the bail being loosely mounted in the hooked end of the bracket.

In testimony whereof I affix my signature.

WILLIAM D. KYLE.
